METHOD OF AND MEANS FOR EXTINGUISHING OR SMOOTHERING EXPLOSIONS IN MINES

Filed April 30, 1921

INVENTOR:
HERMANN KRUSKOPF
ATTORNEY.

UNITED STATES PATENT OFFICE.

HERMANN KRUSKOPF, OF DORTMUND, GERMANY.

METHOD OF AND MEANS FOR EXTINGUISHING OR SMOTHERING EXPLOSIONS IN MINES.

Application filed April 30, 1921. Serial No. 465,785.

To all whom it may concern:

Be it known that I, HERMANN KRUSKOPF, a citizen of the German Republic, and resident of Dortmund, Germany, have invented 5 certain new and useful Improvements in Methods of and Means for Extinguishing or Smothering Explosions in Mines, of which the following is a specification.

My present invention relates to an improved method of extinguishing or smothering explosions in drifts of mines and improving the blasting effects of explosive material in charge-holes by tamping, according to my prior patent applications Serial No. 15 394,597, dated July 7th, 1920, and Serial No. 431,056, dated December 15th, 1920.

a.—Process of extinguishing or smothering explosions in drifts of coal-mines.

20 It has been found by practical experiments that downsand of fine grain is the best material for extinguishing explosions and improving the blasting effect when used as tamping material in charge-holes to be 25 fired.

The results are not equally good if fine downsand is used for extinguishing explosions in drifts of coal-mines. In carrying this process into practical effect, the incombustible dust will be used in tilttable or projecting devices as described in my prior patent applications. Such dust is also spread upon the walls of drifts by means of suitable devices.

35 An explosion produced in drifts causes the incombustible dust to whirl around in a cloud of dust in which the flame of the explosion will be smothered.

Heavy explosions will be extinguished instantaneously by the use of fine downsand, but light explosions in nascent stage will not be smothered unless they are developed to heavy explosions, because they have no sufficient power to cause heavy grain of down-sand, in spite of its fineness, to whirl around and maintain the same suspended in air.

A new improvement of the method of extinguishing or smothering explosions in drifts of coal-mines is as follows:

50 Naturally washed earths which are not baked together or petrified by heat or pressure, have a grain without any sharp edge and of great fineness. Such dust dried by moderate heat of about 100° C., may be 55 crushed or divided to light or flaky dust without sharp edges in mills by little ex-

pense of motive power and in a less expensive way than any other material.

Experiments proved that this kind of dust is capable of smothering even weak or light 60 explosions. A convenient material is furnished for example by clay, argil, lemon, dried at about 100° C. and suitably ground.

b.—Process of extinguishing or smothering explosions in coal-mines and improving the blasting effect of shots by tamping.

From Fig. 3 of the accompanying drawings it will be noted how a paper tube well filled with fine powdered dry downsand is 70 placed as a tamping upon the explosive charge for the purpose of improving the blasting effect thereof and preventing combustible gases and coal-dust from being ignited. The drawing shows that the dust 75 containing tube is of less diameter than the charge hole and inserted loosely into the latter leaving a small free space between it and the charge.

Recent experiments proved that at the moment the charge is fired the cartridge filled with dust will be compressed at the outlet of the charge-hole, thus opposing a heavy resistance, whilst the hollow space between the charge and tamping will be increased. The 80 explosion gases enter said hollow space before they produce their blasting effect. It has been found as new that said hollow space will considerably influence the results of the blasting work. Heavy blasting explosive 85 materials are appreciated in mining owing to their strong action. Heretofore the tamping of charge-holes was formed in most cases of wet clay, suitably and directly placed upon the explosive charge without 90 leaving any hollow space, whereupon said tamping is firmly rammed upon the charge by means of the ramming-bar. This method is considered as being particularly convenient, according to the principle of the density of charge, for a most practical utilization of the explosive material. With this 100 old method it has been found at the moment a shot is fired in a coal-layer, that a large amount of the coal to be blasted will be crushed to dust by the charge adjacent that 105 part of the charge-hole which contains the explosive charge. There occurs only a slight action producing pieces of coal, so that the explosive material will not be utilized in an 110 economical way.

The method according to my present in-

vention produces quite different and much better blasting results. Owing to the said hollow space the pressure surface on which the explosion gases produce their pressure will be considerably increased. At the same time the pressure of the explosion gases will be reduced to a certain extent in direct relation to the increase of the pressure surface within the charge-hole. Furthermore the pressure will be improved by a more complete combustion of the explosive charge. Practical experiments proved that the explosive material will be utilized in a more economical way. By the method according to this invention coal will be broken into large pieces. It has been found that 20 to 50% of explosive material may be saved according to particular circumstances. By firing shots according to the old method this amount of explosive material was uselessly spoiled for crushing coal to dust in the neighbourhood of the explosive charge. The perfect combustion of the explosive charge owing to the hollow space may be noted in the form of soft after-damps. Experiments proved that the improved blasting effect depends on the size of the hollow space between the charge and the tamping, and a certain size of the grain of the dust used, as well as on the compact uniform filling of the tamping cartridge. These conditions may be most easily fulfilled by the use of a paper tube filled with fine dust, said tube being inserted longitudinally into the portion of the charge-hole left free by the charge, the tube being preferably of less diameter than the charge-hole. The cartridge will be inserted loosely without ramming. In contradistinction to the old pasty rammed tamping my improved form of dust cartridge has the advantage that in the event of misfired shots they may be easily withdrawn from the charge-hole without any danger. The misfired charge can thus be provided with a fresh primer.

The hollow space may also be formed by means of separate bodies of smaller diameter, for example wooden rods, suitably shaped small pieces of stones or similar bodies of suitable shape and material. In this method the remaining space at the outlet of the charge-hole may be filled up with a suitable pasty or powdered tamping, the diameter of which is or may be equal to or less than the diameter of the charge-hole.

The new objects of my present invention are:

1. To use light or flaky dust without sharp edged corners, obtained from naturally washed earth which is not petrified by heat or pressure, such earth being dried at low heat and ground to dust by suitable power, for the purpose of extinguishing explosions in drifts of coal-mines by the whirl-

ing around of said dust under the action of the pressure of explosions.

2. To provide a hollow space, by suitable means as herein described, between the charge and the tamping in charge enclosed in charge-holes for improving the blasting effect.

An example of practical embodiment is illustrated in the accompanying drawings.

Fig. 3 shows the shot in a layer of coal ready to be fired and tamped according to my improved method. *c-d* is the charge, *a-e* is a paper tube filled with fine sand of less diameter than the charge-hole and extending over the entire length of the latter. There is a hollow space *e-e*, formed by loosely inserting said paper tube. *k* designates conducting wires for the ignition of the explosive charge. *l* indicates the lower cut of the coal to be blast.

Fig. 4, *c-d* is the explosive charge with the charge-hole; *a-e* is a tamping without paper tube formed of fine, dry or pasty wet material; *f-e* is the hollow space. Said hollow space *f-e* is formed by leaving unfilled a portion of the charge-hole in any suitable way for instance by making a mark on the ramming bar or the like. The tamping will be inserted into the charge-hole by means of suitable devices, for instance in the event of a pasty tamping by means of the ramming bar, in the event of a powdered tamping by means of a tube containing the same and emptied within the charge-hole by blowing into or by inserting a rod through said tube.

Fig. 1 shows a firmly rammed clay or argil tamping according to the old method. The argil or clay tamping *b-c* is placed directly, without a hollow space, upon the explosive charge *c-d*. It is customary to fill the free portion of the charge-hole only to 1/3 with the tamping.

Fig. 2 shows how at the moment of the firing the hollow space *c-e* has been increased by the compression of the tamping. The explosion gases entered the same before producing their blasting effect. After being compressed said tamping closes the charge-hole in a gas-tight way with great resistance to pressure owing to its great length. The pressure surface on which the gases entering the hollow space produce their blasting effect, has also been increased in proportion to the increase of the hollow space.

Fig. 5 shows a tamping in which the hollow space is formed by means of a suitably shaped distance body *b*. *a* is the explosive charge. *c* is a tamping filling the full diameter of the charge-hole.

In Fig. 6, *a¹* is a cross section through the charge containing portion of the charge-hole. *b¹* and *b²* are cross sections through different shapes of rectangular distance bodies. *c¹*

and e^2 are cross sections through tampings made of equal or less diameter respectively than the charge-hole.

Fig. 7 shows various forms of tampings 5 with distance bodies numbered 8 to 12 respectively.

Said distance bodies are formed of incombustible materials.

A powdered tamping according to my invention 10 may be easily filled into tubes. Besides the easy filling, this has the advantage that the kind and amount of dust may be easily controlled. Misfired shots may be easily discharged by simply withdrawing 15 the tubes filled with fine dust.

For certain reasons the paper tube may also be omitted, in which case dust will be suitably filled into the charge-hole without tube, a suitable hollow space being left between 20 it and the charge as shown in Fig. 4 with a good blasting effect as a result, provided that the grain of the dust and size of said hollow space will be adequately chosen according to experiments.

Having now fully described my said invention, what I claim and desire to secure by Letters Patent, is:

1. The herein described method of tamping explosive-charge holes, consisting in inserting in such hole, following the application 30 of the charge, a self-contained charge of tamping material having a normal diameter less than that of the hole, said material being released under the force of the explosion to eventually completely close the tamped end of the hole.

2. The herein described method of tamping explosive-charge holes, consisting in inserting in such hole, following the application of the charge, a self-contained charge 40 of incombustible dust.

3. The herein described method of tamping explosive-charge holes, consisting in inserting in such hole, following the application of the charge, a charge of incombustible 45 dust arranged in a frangible container having a diameter less than that of the charge hole.

4. A tamping for charge holes, comprising a frangible container of smaller diameter than 50 the charge hole filled with an incombustible dust.

5. The herein described method of tamping explosive-charge holes, consisting in inserting in such hole following the application of the charge, an independent spacing member adapted to have one end engage the charge, and a self-contained charge of tamping material having a normal diameter less than that of the hole inserted to engage the 60 other end of the member, the member spacing the charge and tamping in a predetermined relation and said material being released under the force of the explosion to eventually completely close the tamped end 65 of the hole.

In testimony whereof I have hereunto set my hand in presence of two witnesses:

HERMANN KRUSKOPF.
